POT TYPE FUEL OIL BURNER

John W. Thomson, Oakland, Calif., assignor to
 Benner-Nawman, Inc., Oakland, Calif., a corpora-
 tion of California

Application December 29, 1950, Serial No. 203,360

4 Claims. (Cl. 158—91)

1

This invention relates to oil burners of the so-called pot type in which oil is admitted to the bottom of the pot or container where it is vaporized, thence while in such form and rising in the container is mixed with air to form a combustible mixture which will issue from the throat of the container in a burning mass. More particularly the present invention is an improvement upon the burner described and claimed in my Patent No. 2,542,729, issued February 20, 1951.

An object of the present invention is to provide an oil burner of the character described in which the air which is directed into the portion of the pot in which the oil is being vaporized, is confined to a point immediately above but spaced from the vaporizing surface of the oil on the bottom of the pot, so that while adequate air is available for admixture with the fuel immediately after vaporization, said air will not impinge on such surface so as to impede vaporization or cool the area of the pot on or adjacent which vaporization is being effected.

Another object of the invention is to provide an effective means of preheating the air which enters the pot, and particularly the air which is directed into the oil vaporization zone of the pot.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to the drawing:

Figure 1 is a fragmentary perspective view of the burner.

Figure 2 is a vertical transverse sectional view of the burner.

Figure 3 is a vertical longitudinal sectional view of the burner taken in the line 3—3 of Figure 2.

Figure 4 is a top plan of the burner unit on a much smaller scale than in the other views.

In the drawings, the oil burner, designated generally by the numeral 5, is embodied in a unit particularly adapted for incorporation in furnaces and heaters for domestic use. As here shown, the unit includes a rectangularly-shaped housing 6 having top and bottom walls 7 and 8, side walls 9, and end walls 11 and 12. The burner or burner casing 5 is arranged within the housing adjacent the end wall 12 thereof, and comprises in general corresponding side walls 13, end walls 14 and 15, and a bottom wall 17, such side, 55

end, and bottom walls defining a rectangular space in which at different stages, the oil is vaporized, the vaporized oil is admixed with air to form a combustible mixture, and the latter burned in a mass which discharges from said space at the top thereof. The aforesaid walls of the burner are preferably formed of sheet metal and welded or otherwise secured together to provide a unitary structure. As here shown, to accommodate the burner, the top wall 7 of the housing 6 is formed with an open portion in which the burner is inserted, the latter being supported in position by means of flanges 18 and 19 which extend respectively from the side and end walls 15 of the burner and rest on portions of the top wall 7 surrounding the open portion aforesaid. Screws 21 or the like serve to secure the flanges to wall 7.

The walls 13 of the burner extend parallel to and are spaced from the side walls 9 of the housing, and correspondingly the end walls of the burner extend parallel and are spaced from the end walls of the housing, however the spacing between the end wall 12 of housing and adjacent end wall of the burner is considerably less than the space between the other end wall of the burner and the end wall 11 of the housing. In addition to the above spacing, the bottom wall of the burner as well as the lower edges of the side and end walls thereof are spaced from the bottom wall 8 of the housing as will be clear from Figures 2 and 3. All of the spaces aforesaid combine to form an air chamber into which fresh air is forced by means of a blower 24 mounted at the end of the housing having the greater space with the opposing end of the burner.

Oil in liquid form is arranged to be supplied to the burner in desired regulated amount, through means of a pipe 26 which extends through the space under the bottom wall of the burner and is connected to such wall by means of an elbow 40 27, the free end 28 of the latter being projected upwardly through a depression 29 in said wall and terminating at a level below the inside surface of the wall. A perforated disc or screen 31 is fitted in such depression and overlies the end 28 of the elbow, the upper surface of the screen being flush with the corresponding surface of the bottom wall of the burner so that a substantially continuous flat horizontal surface will be provided for the entire floor of the burner. It may be noted that the thickness of the screen as well as the bottom wall 17 including the depressed portion 29, is the same throughout and insures an even and uniform heating of these members when the burner is in operation.

Preferably both end walls of the burner are

vertical, but the side walls, while generally upright, are each formed with oblique portions in angular relation to each other. Thus as will be clear from Figures 1 and 2, each wall 13 is composed of an upper section 32 and a lower section 33. The two upper sections together with portions of the end walls form a combustion chamber 34 whereas the lower sections together with a portion of the end walls define an oil vaporizing chamber 36. The lower sections 33 extend convergently upward from the bottom of the burner to the lower terminus of the upper sections, and the latter sections extend divergently upward from said terminus to the top of the burner, the opening between said upper sections at the top constituting the throat of the burner. Perforations 37 provided in the upper sections, form inlet passages through which air from the housing is directed in streams across and upwardly into the combustion chamber 34, such streams furnishing secondary air for admixture with the vaporized oil ascending from the chamber 36.

In the operation of the burner, oil in liquid form is admitted to the bottom of the burner, and the wall 17 is maintained at such a temperature as to cause vaporization of the oil as soon as it spreads over the flat upper surface of such wall. Preheating of the oil entering the vaporization chamber is effected as the oil passes through the openings in the screen 31 which is also maintained at a high temperature.

Passages 38 are provided in the wall sections 33 of the vaporization chamber in order to admit primary air to such chamber and it has been found of utmost importance to prevent such incoming air from cooling the exposed surface of the film of oil spread over the floor of the burner, the vaporization of the oil as will be understood, being largely effected at such surface. An important feature therefore of the present invention is to arrange the openings or passages 38 in such a manner as to direct and confine the incoming streams of air in the vaporization chamber so that ample primary air is supplied without curtailing the oil vaporizing action. In accordance with the above, the openings 38 instead of being distributed over the entire area of the wall sections 33, as is more or less the case in respect to the openings 37 in the upper sections 32, are confined to the upper portion of the sections 33 so that the streams directed into the vaporization chamber will either impinge directly on the wall opposite or strike the opposing stream. In either case, the force of the stream will be dissipated before contact may be made with the vaporizing oil film on the bottom of the burner. As will be clear from Figure 2, while in the embodiment illustrated, the axes of the passages 38 are perpendicular to the wall section in which they are contained, and the angle of such sections is such as to cause intersection of the streams from opposing sections at a point high enough above the bottom of the burner to afford almost immediate contact with the rising vaporized oil, without possibility of the air streams impinging directly on or cooling the vaporizing surface of the oil film on said bottom. For example, where the width of the burner bottom is about two inches, and the sections 33 are approximately three quarters of an inch in height and at an angle of about 9.2 degrees to the vertical, the center of the passages 38 are preferably between one-eighth to three-sixteenths of an inch from upper terminus of such sections.

With this relationship the distance between the point of intersection of the axes of opposing streams and the top surface of bottom of the burner will be approximately one quarter of an inch.

Incidentally in keeping with the above relationship, the vertical height of the upper sections would be preferably about two and three eighths inches and the inclination thereof should be about 28 degrees from the vertical. With this relationship a thorough admixture of secondary air will be produced in the combustion chamber and an efficiently burning mass will be discharged from the burner throat.

Variation in the capacity of the burner may be obtained by retaining the above relationship of the burner parts but varying the length of the burner.

Another important feature of the present invention resides in providing a simple means for preheating the air which passes into the burner through the openings 37 and 38. As will be seen from the drawings, there is preferably provided at the sides of walls 13 deflectors 39 which serve to guide and distribute the air in the housing to the openings 37 and 38. The deflectors are preferably disposed parallel to the upper wall sections and are supplemental with arcuately shaped attachments 41 which serve to smoothly guide the air upwardly around the deflectors to the space or chamber 42 between the deflectors and the wall sections. Inserted in said chambers 42 is a filling of metallic fibres 43 such as "steel wool," the fibres being rather loosely instead of tightly packed in the chambers so that the incoming air may readily pass therethrough. As will be understood the fibres will become heated during the operation of the burner and provide a thorough preheating of the air about to enter the openings 37 and 38. This will result in a more effective admixture of both the primary and secondary air with the fuel vapor, and in a corresponding more efficient operation of the burner.

Desirably and as will be clear from Figures 1 and 3, a concentration of air openings 37 is provided near the throat of the burner, and in order to prevent the flame from burning up over and spreading laterally from the throat, a deflector strip 43 is positioned just above said top openings and extends for the full width of the side walls.

I claim:

1. In an oil burner, a burner casing having opposing side walls and opposing end walls, said casing having an opening at the top providing a burner throat and a flat wall forming the bottom of the interior of the burner, said side walls having lower sections extending in convergent relation upwardly from said bottom wall to define with lower portions of said end walls an oil vaporizing chamber, and said side walls having upper sections extending angularly upwardly from said lower sections and defining with the upper portions of said end walls a combustion chamber communicating with said vaporization chamber, means to supply a film of oil over said bottom of the burner, air inlet means in said upper wall sections, and air inlet means in said lower wall sections providing for sole supply of air to said vaporization chamber from the exterior of the burner, said means directing air streams into and across said vaporization chamber exclusively above and spaced from the oil level in said chamber.

2. In a rectangular pot-type oil burner, a burner casing having opposing side walls and opposing end walls, said casing having an opening adjacent the top providing a burner throat and a flat wall forming the bottom of the interior of the burner, said side walls having lower sections extending in convergent relation upwardly from said bottom wall to define with lower portions of said end walls an oil vaporization chamber, and said side walls having upper sections extending divergently upward from said lower sections to define a combustion chamber communicating with said vaporization chamber, means to supply a film of oil to the bottom of said vaporization chamber, and air inlet means for said vaporization chamber confined exclusively to said lower section and so formed and positioned as to direct air streams across and downwardly into said vaporization chamber and so as to avoid direct contact with the oil film on said bottom wall.

3. In a rectangular pot-type oil burner, a burner casing having opposing side walls and opposing end walls, said casing having an opening adjacent the top providing a burner throat and a flat wall forming the bottom of the interior of the burner, said side walls having lower sections extending in convergent relation upwardly from said bottom wall to define with lower portions of said end walls an oil vaporizing chamber and said side walls having upper sections extending divergently upward from said lower sections to define a combustion chamber communicating with said vaporization chamber, means to supply a film of oil to the bottom of said vaporization chamber, and air inlet means in and confined to the upper portion of the opposed lower sections directing air downwardly into and across said vaporization

chamber along axes intersecting at a point above and spaced from the bottom of the burner.

4. In a rectangular pot-type oil burner, a casing provided with opposing side walls and opposing end walls and with a burner throat at the top and a flat wall at the bottom, the lower portion of said side walls converging upwardly from said bottom wall and defining with the lower portion of said end walls an oil vaporization chamber communicating at the top with the space between the upper portions of the side and end walls, means to supply a film of oil over said bottom wall including a depressed portion provided centrally in said bottom wall, a supply pipe projecting upwardly through said depressed portion with its upper end spaced from the sides thereof and below the plane of said bottom wall whereby an oil well will be defined around and above said pipe end, a screen covering said depression coplanar with said bottom wall, and air supply means for said vaporization chamber including air inlet openings provided exclusively in the upper portion of said lower side wall sections and so arranged as to guide the streams of air downwardly and across the vaporization chamber without contacting the oil film on said bottom.
